VACUUM SEALED CASKET

Harry J. Kimmel, Seattle, Wash., assignor of one-third to Henry A. De Long, Seattle, Wash.

Application April 11, 1950, Serial No. 155,260

2 Claims. (Cl. 27—7)

1

This invention relates to burial caskets, and in particular means for positively sealing a casket for preserving a body therein.

The purpose of this invention is to provide means for hermetically sealing a casket in which a preservative or moisture absorbing fluid may be injected into the casket and withdrawn or sealed therein.

Various attempts have been made to seal caskets by the use of gaskets and other sealing means, however, gaskets of the resilient type deteriorate with age and devices of this type are not satisfactory for indefinite use. With this thought in mind this invention contemplates a casket formed of plastic with a continuous tongue on the under surface of the cover positioned in a corresponding groove at the upper edge of the wall of the casket wherein a solvent such as acetone, may be placed in the groove for softening surfaces of the tongue and groove to positively seal the parts and in which a valve may be provided through the wall of the casket for injecting fluid or for withdrawing fluid to provide a vacuum therein and wherein the valve is provided with a plastic point that is also sealed by a solvent or the like. The object of this invention is, therefore, to provide means for forming a casket whereby the casket is positively and permanently sealed.

Another object of the invention is to provide a sealed casket that may be formed of transparent material whereby the contents are visible at all times.

A further object of the invention is to provide a casket having positive and permanent sealing means which is of simple and economical construction.

With these and other objects and advantages in view the invention embodies a casket having a groove in a continuous bead around the upper edge with a cover having a tongue corresponding with the groove and with a valve in combination with a filling plug in a cavity extended through the wall of the casket and formed of materials for positive sealing.

Other features and advantages of the invention will appear from the following description taken in connection with the drawings wherein:

Figure 1 is a side elevational view of the casket with the cover slightly raised above the upper end of the wall thereof and with parts broken away and shown in section.

Figure 2 is a plan view of the casket shown in Figure 1 with the cover removed.

Figure 3 is a cross section through the casket taken on line 3—3 of Figure 1.

2

Figure 4 is a detail on an enlarged scale showing a section through one side of the casket and cover and illustrating a valve positioned in an inlet opening through the cover and wall of the casket.

Figure 5 is a similar view showing the valve sealed.

Figure 6 is a detail showing a typical section through a corner of the casket and cover with the parts in the sealed positions.

Figure 7 is a detail on an enlarged scale showing a section through a corner of the casket and cover with an escape plug and also a sealing plug mounted in the cover.

Referring now to the drawings wherein like reference characters denote corresponding parts the sealed casket of this invention includes a box-like portion 10, a cover 11, an inlet valve 12 in the body portion and an escape plug 13 in the cover.

The body portion 10 is formed with a bottom 14 having a continuous upwardly extended wall 15 with a bead 16 having a groove 17 in the upper surface extended around the upper edge and, as illustrated in Figure 2 the inner surface of the wall is bulged inwardly at the point 18 providing an inner arcuate section 19 of the groove with a boss 20 surrounded by the groove and through which an opening 21 extends, as illustrated in Figure 4.

The cover 11 is provided with a continuous tongue 22 that extends downwardly into the groove 17 with the cover on the body portion, and the cover may also be provided with an arcuate section 23 of the tongue that extends into the section 19 of the groove also as shown in Figure 4.

The valve 12 which is preferably formed of plastic, is carried on the end of a stem 24 of a threaded section 25 and the section 25 is threaded in a bushing 26 that is positioned in a boss 27 on the wall of the casket. The stem 24 is provided with a knurled head 28 by which the valve 12 may be adjusted to open or close, an opening 29 extended from the valve seat 30. The opening 21 also communicates with a chamber around the valve seat, as indicated by the numeral 31 and, as illustrated in Figure 4 the upper end of the opening 21 communicates with a registering opening 32 in the cover 11, the upper end of which is provided with a threaded bushing 33. A sleeve 34 may also be provided in the lower end of the opening 32 and, as shown in the drawing, the sleeve 34 may extend into the upper end of the opening 21.

When sufficient material has been injected into

or withdrawn through the openings 29, 21 and 32 the valve may be closed against the seat and a plug 35 may be threaded into the bushing 33 to close the opening. With the cover, wall of the casket and the valve 12 formed of plastic, a solvent, as indicated by the numeral 36 may be poured into the openings whereby the valve and associated elements are positively sealed.

With a similar solvent positioned in the grooves 17 in the upper edge of the body portion of the casket the solvent will be forced over the adjoining surfaces of the cover and casket as indicated by the numeral 37 in Figure 5 and with the cover secured in position by vacuum the solvent will soften the surfaces of the cover and casket whereby a positive bond will be obtained between the elements and the casket will be sealed.

The cover 11 may also be provided with a boss, as indicated by the numeral 38 and a cavity 39 is extended through the cover and boss with a threaded bushing 40 in the outer end of the cavity and in which the plug 43 is threaded, as shown in Figure 7. The cavity 39 is also provided with a side connection 41 that extends through a threaded opening 42 in which a sealing plug 43 is positioned.

By this means gases or other fluids may be withdrawn from the casket through the cavity 39 and after the fluids have been exhausted the plug 43 is inserted to seal the outer end of the cavity and a solvent is placed through the side connection 41. After the solvent is in place the plug 43 is inserted to seal the outer end of the cavity 41.

The body portion and cover of the casket may be formed of transparent material or the material may be opaque, translucent, or of any suitable color.

With the parts formed in this manner the moisture absorbing fluid may be forced into the casket under pressure whereby substantially all moisture may be eliminated from the casket and this fluid and also all other gas in the casket may be withdrawn to provide a vacuum whereby an embalmed body may be preserved indefinitely. It will also be understood that the casket may be filled with a preserving gas or liquid and this

fluid may also be sealed in the casket if desired.

By forming the parts of plastic and also forming the valve elements of the same material solvent introduced into the grooves and connecting openings of the valve provide a positive seal in and around the valve and also between the casket and cover.

It will be understood that modifications may be made in the design and arrangement of the parts without departing from the spirit of the invention.

What is claimed is:

1. A sealing casket comprising a box-like plastic casing having a bottom with a continuous wall 15 extended upwardly therefrom, said casing having an opening with a valve seat therein extended through the wall thereof and also having an intersecting opening extended from the opening having the valve seat therein upwardly through the upper part of the wall of the casing, a threaded bushing positioned in the opening in the wall of the casing, and a valve threaded in the bushing in the opening.

2. In a sealing casket, a box-like plastic casing 20 having a bottom wall with a continuous wall extended upwardly therefrom, said casing having an opening with a valve seat therein extended through the wall thereof and also having an intersecting opening extended from the opening 25 having the valve seat therein upwardly through the upper part of the wall of the casing, and a valve for said valve seat.

HARRY J. KIMMEL.
